COLLAPSIBLE FORM FOR FORMING WINDOW OR DOOR OPENINGS IN CONCRETE WALLS

Patrick J. Callan, Manhasset, N. Y.

Application June 12, 1948, Serial No. 32,695

2 Claims. (Cl. 25—128)

1

This invention relates to forms for making poured concrete homes or buildings and more particularly to the forms used about the window and door openings.

In my pending application, Serial No. 736,685, filed March 24, 1947, now Patent No. 2,546,427 there is disclosed and claimed collapsible form arrangement for concrete wall construction of a type adapted to be set up so that an entire story of a house or the like can be poured with concrete at one time and wherein the assemblage of forms can be removed as units and set up on another foundation in short order to pour the next house. The forms for the interior of an entire room is pulled out of the top of the poured concrete. With these forms provision is made for effecting the forming of window and door openings as the concrete is poured.

It is an object of the present invention to provide releasable door and window opening forms adapted to be used with the wall forms disclosed in my pending application and which are adapted to be retained by a set of levers located in the respective corners of the forms and which can be contracted to permit their easy removal from the wall forms without being disassembled and which can be moved to a new building site as a unit for reinsertion in the building wall forms when they too are located on the new site.

It is another object of the present invention to provide collapsible door and window opening forms which are adapted to be inserted between spaced wall forms and which have portions permitting the easy securement to the wall forms at locations interiorly of the window forms and in such a manner that the window or door opening will be formed in a smooth condition without being frayed and without work having to be done upon these openings when the forms of the same have been removed and wherein these forms will support anchor members adapted to be embedded in the concrete and serve as means to which hinges or the like fixtures for an opening may be attached when the forms have been removed.

Other objects of the present invention are to provide collapsible window and door opening forms adapted for use with poured concrete wall forms which are of simple construction, easy to assemble and install in the building wall form, inexpensive to manufacture, easy to release, which can be moved as a unit and efficient in operation.

For other objects and for a better understanding of the invention, reference may be had to the following detailed description taken in connection with the accompanying drawing, in which

2

Fig. 1 is an elevational view of the door or window forms extended and locked in a wall form and embodying the features of the present invention.

5 Fig. 2 is an enlarged sectional view taken on line 2—2 of Fig. 1 and showing one means of bracing the wall forms on the opposite sides of the window or door opening frame, this figure bearing the line 1—1 on which the view of Fig. 1 was taken.

Fig. 3 is a fragmentary and sectional view of a portion of the wall which is made with these forms and looking in elevation upon one side edge of the window opening thereof.

15 Fig. 4 is a detail sectional view taken through the projections on which the locking lever is pivoted and on line 4—4 of Fig. 1.

Fig. 5 is a fragmentary sectional view looking in plan upon the locking lever and upon its connection with the form, the view being taken on line 5—5 of Fig. 1.

20 Fig. 6 is a fragmentary sectional view taken on line 6—6 of Fig. 1 and showing an internal lug or sleeve formation by which a bolt is retained for the connection of the opening form with the building wall form.

Fig. 7 is a fragmentary sectional view showing an anchor member retained on the form for the purpose of being supported while the concrete is being poured around the same, the view being taken on line 7—7 of Fig. 1.

25 Fig. 8 is a perspective view of one type of anchor member.

Fig. 9 is a fragmentary sectional view of the 30 form showing a supporting bracket for insulating material which is placed centrally of the wall forms to have concrete poured on the opposite sides of the same and whereby the window or door opening form serves as a support for this insulating material.

Fig. 10 is a perspective view of the insulating material supporting member connected to the form as shown in Fig. 9.

35 Fig. 11 is a fragmentary side elevational view of two adjoining form pieces with the locking lever pulled and pieces collapsed.

Referring now to the figures, 15 and 16 are respectively portions of the building wall forms between which my window or door opening forms 50 17 are disposed as a unit, Figs. 1 and 2, and are retained against lateral displacement by the extension of bolts 18 through one of the wall form plates into sleeve projections 19 weldingly secured as indicated at 21 at different locations within the window form and on the inwardly collapsible side pieces 22, 23, 24 and 25 thereof. A net 26

and washer 27 is placed on the bolt and tightened whereby to draw the form tightly upon the wall form plate.

The wall form plates 15 and 16 are further retained flush against the edges of the window form 17 by long bolts 28 passing through openings 31 and 32 in the respective plates, Fig. 2, and through I-beams lying flush upon the exteriors of the plates 15 and 16 as indicated respectively at 33 and 34. A nut 35 is extended on the bolt to draw the beams 33 and 34 and the plates 15 and 16 together and onto the edges of the window or door opening forms.

Each of the form pieces have a shoulder formation 36 serving to provide a jamb 37 in the finished opening of wall 38, Fig. 3. The pieces are also flared at opposite sides as indicated at 39 and 40 to provide bevel edges 41 and 42 respectively.

Each of the form pieces have a corner as indicated at 43 and from which extend a short side 44 beveled as indicated at 45 to match with a bevel face 46 of a long side 47 of an adjacent piece, Figs. 1 and 11. Extending from each corner 43 are spaced projections 48 and 49 between which is extended a U-shaped locking lever 50. This lever is pivotally connected to the projections by a bolt 51, Fig. 4. The bolt 51 is held in place by a nut 52. The projections 48 and 49 are welded in place as indicated respectively at 53 and 54, Fig. 4.

A long portion 47 of a piece has a projection 55 adjacent the beveled end 46 and which extends inwardly through the U-shaped locking lever and is pivotally connected thereto by a bolt 56. The lever has a handle portion 57 which is grasped to pivot the lever and upon the lever being pushed outwardly from the position shown in Fig. 11 to the position shown in Fig. 1, the beveled faces 46 and 45 of the pieces are brought together. The lever will be held in its adjusted position by a hook bolt 58 which extends through the lever and has a thumb nut 59 thereon. This nut 59 will be tightened to secure the lever 50 in place. When it is desired to free the form 17 from the concrete, the thumb nut 59 is loosened and the locking lever 56 brought inwardly whereby to overlap the pieces at their bevel faces and in the manner shown in Fig. 11 to reduce the overall size of the form and to permit its withdrawal from the forms. The hook bolt 58 is extended over a notched projection 60.

In order that hinge brackets will be embedded in the sides of the concrete opening when the form is removed, a bracket 62, Fig. 8, is secured to form piece 22 as shown in Fig. 7 with a recess forming plate 63 into which the hinge part may fit when the forms have been removed. The piece 63 and the bracket or anchor member 62 is secured to the frame piece 22 by a removable screw 64. Before the forms are removed, the screw 64 is removed. Thereafter the recess-forming plate 63 can be removed and replaced with a hinge or fixture plate. The anchor member or hinge bracket has threaded openings 65 for receiving the screw 64.

The form 17 may also serve to support a U-shaped retaining bracket 66 for an insulating member 67 to be surrounded with concrete and embedded in the finished wall. The bracket 66 will be left in the side of the opening and may serve for the attachment to the opening of a fixture. The bracket is held on the form by a screw 68 entering threaded opening 69 of the bracket. This screw 68 will be removed at the time the form is removed.

It should now be apparent that there has been provided a window or door opening form which can be fitted into the building wall forms disclosed in the above mentioned patent application and secured thereto in a releasable manner. The form will be held against lateral displacement by direct connection with the building wall form plates and the building wall form plates will be held against outward buckling movement by tie members extending through the door or window form and connected to I-beams lying flush against the exteriors of the building wall form plates. It will be further apparent that the pieces making up the form can be collapsed inwardly to permit the removal of the form from the concrete opening and without the individual pieces being disassembled. These pieces are thus maintained in assembled relationship and delivered as a unit to the new site for another concrete building. It will be further apparent that the frame pieces serve as supports for anchors to which fixtures can be attached, the anchors being embedded in the sides of the opening.

While various changes may be made in the detail construction, it shall be understood that such changes shall be within the spirit and scope of the present invention as defined by the appended claims.

I claim:

1. A collapsible window or door opening concrete form adapted for use with concrete building wall forms comprising a plurality of separable corner-shaped pieces arranged in a cluster and adjustable relative to each other, each of said corner-shaped pieces having a long leg portion and short leg portion, these portions being cut on an opposite bias to match with one another when assembled for use in the building wall forms, projection means extending inwardly from the short leg portion and projection means extending inwardly from the long leg portion substantially adjacent the projection means on the short leg portion, locking levers respectively disposed in the corners of the form and respectively pivotally connected at one end to the projection means on the short leg portions and pivotally connected to the projection means on the long leg portions of the adjacent corner pieces and having a working handle at the opposite end thereof, said locking levers being operable upon the pieces either to forcibly expand the leg portions of the adjacent pieces into their aligned assembled positions or to forcibly collapse the long leg portions to draw the pieces together whereby to permit the removal of the form from the completed concrete structure and retaining means on the respective long leg portions and connected to locking levers to hold the levers in their locking positions.

2. A collapsible window or door opening concrete form adapted for use with concrete building wall forms comprising a plurality of separable corner-shaped pieces arranged in a cluster and adjustable relative to each other, each of said corner-shaped pieces having a long leg portion and short leg portion, these portions being cut on an opposite bias to match with one another when assembled for use in the building wall forms, projection means extending inwardly from the short leg portion and a projection extending inwardly from the long leg portion substantially adjacent the projection means on the short leg portion, U-shaped locking levers respectively disposed in the corners of the form and

respectively pivotally connected at one end to the projection means on the short leg portion and pivotally connected to the projection on the long leg portions of the adjacent corner pieces and lying astraddle thereof, said locking levers being operable upon the pieces either to forcibly expand the leg portions of the adjacent pieces into their aligned assembled positions or to forcibly collapse the long leg portions to draw the pieces together whereby to permit the removal of the form from the completed concrete structure, each of the projections on the long leg portions of the pieces having a notch formation, a hook bolt extending over the notch formation and adapted to extend through the lever when in its locking position and a nut on the bolt and engageable with the lever to hold it in its locking position.
